Attorney's

UNITED STATES PATENT OFFICE.

HENRY P. DECKERT, OF MARION JUNCTION, SOUTH DAKOTA.

WRENCH.

No. 874,742.

Specification of Letters Patent.

Patented Dec. 24, 1907.

Application filed June 14, 1907. Serial No. 378,963.

To all whom it may concern:

Be it known that I, HENRY P. DECKERT, a citizen of the United States, residing at Marion Junction, in the county of Turner, State of South Dakota, have invented certain new and useful Improvements in Wrenches; and I do hereby declare the following to be a full, clear, and exact description of the invention, such as will enable others skilled in the art to which it appertains to make and use the same.

This invention relates to ratchet wrenches and has for its object to provide a wrench of this character which will be applicable to any ordinary size of nut.

In order that the wrench may be adjusted as above stated, I have formed through the head of the wrench an elongated nut receiving opening, and adjustable in this opening by reason of its swivel connection with a set screw, is a plate which coöperates with one end wall and with the side walls of the opening to embrace the nut.

In the accompanying drawings, Figure 1 is a side elevation of a wrench constructed in accordance with my invention, Fig. 2 is a bottom plan view thereof, Fig. 3 is a vertical longitudinal sectional view through the head and a portion of the handle of the wrench, Fig. 4 is a detail horizontal sectional view taken through the head and a portion of the handle and showing the ratchet mechanism of the wrench, and, Fig. 5 is a detail perspective view of the plate and the set screw connected therewith. Fig. 6 is a detail vertical longitudinal sectional view through the sleeve.

As shown in the drawings the wrench comprises a head 6 which is substantially cylindrical in form and includes a reduced portion 7 with which latter is rotatably engaged a two-part collar portion 8, formed integral with one end of the handle 9 of the wrench, there being an annular rack element 10 received between the two members of the collar portion 8. Coöoperating with this rack element 10 is a pawl device which will be presently more specifically described.

Formed through the head 6 and opening through the ends thereof is an elongated opening 11 and engaged through one side of the said head 6 and extending into the said opening, through one end wall thereof, is a set screw 12 to the outer end of which is swiveled a plate 13, which plate is substantially rectangular in form and is of such

width that its side edges abut the side walls of the opening 11. One face of the plate 13 opposes that end wall of the opening other than the one through which the set screw 12 is engaged and the said plate coöperates with the said end wall and with the side walls of the opening, to form a nut receiving opening, it being understood that the plate 13 is adjustable, to and from the said end wall, by turning the set screw 12 and that consequently a nut of any ordinary size may be received in the nut receiving opening. In order that the plate 13 may be guided in the opening 11, grooves 12' are formed in the side walls of the opening and lugs 13' are formed at the side edges of the plate 13 and work in the grooves.

That portion of the handle 9 of the wrench with which the collar portions 7 are formed integral, is bifurcated as at 14 and pivoted in the bifurcation are pawls 15, the pivots for the pawls being indicated by the numeral 16. Each of these pawls includes a toothed or working portion 17 which coöperates with the annular rack element 10 of the wrench at one side thereof, the pawls being held in such engagement by means of springs 18 which seat at one of their ends in sockets 19 formed in the vertical wall of the bifurcation 14 and at their opposite ends seat in similar sockets formed in lugs 20, formed integral with respect to the pawls. These lugs 20 project outwardly of the bifurcation and have their forward sides rounded as at 21.

In order that the pawls may be independently brought into engagement with the ratchet 10, a sleeve 22 is engaged upon the handle of the wrench directly rearwardly of the two-part collar portion, the sleeve being adapted for rotation upon the handle but being limited in its movement by a pin 23 which is removably fixed in the handle and which works in a recess or cut-away portion 24 formed at the inner end of the sleeve it being understood that the formation of this recess results in shoulders 25 which abut against the said pin 23 when the sleeve is at either limit of its rotary movement. Internally the sleeve is provided with a continuous annular groove 26. The interior wall of the sleeve is also recessed at diametrically opposite points as at 27 so that the sleeve may be slipped over the handle and the heads 20 of the pawls be permitted to pass, by way of the recesses into the groove 26. This groove is contracted as at 28 at one side

and between the recesses 27. By contracting this groove a cam 29 is formed which rides over one or the other of the pawl heads 20 when the sleeve is rotated to move one or the other of the pawls out of engagement with the ratchet 10.

What is claimed, is—

A wrench of the class described comprising a head, a handle, the head being reduced 10 for substantially one-half its length and provided with a nut receiving opening in its un-reduced end, a two-part collar portion formed integral with one end of the handle and receiving the reduced portion of the 15 head, an annular ratchet fixed upon the reduced portion of the head between the collars of the said collar portion, the handle being bifurcated at that end at which the two-part collar portion is formed, pawls piv-

oted in the bifurcation and adapted to co- 20 operate independently with the ratchet, springs tending to hold the pawls in such engagement, a lug formed integral with each of the pawls, and a sleeve rotatably fixed upon the handle and inclosing the said bifurcated 25 portion thereof, the sleeve being provided interiorly with an annular groove which is contracted to form a cam portion which is adapted to ride over one or the other of the pawl lugs to move the corresponding pawl 30 from engagement with the ratchet.

In testimony whereof, I affix my signature in presence of two witnesses.

HENRY P. DECKERT.
